UNITED STATES PATENT OFFICE.

KARL FROST AND OSWALD JESSL, OF CHICAGO, ILLINOIS.

DESIGN FOR A COMBINATION TOOTHBRUSH, PASTE, AND GLASS HOLDER.

59,647.

Specification for Design.

Patented Nov. 15, 1921.

Application filed June 4, 1921. Serial No. 475,110. Term of patent 7 years.

To all whom it may concern:

Be it known that we, KARL FROST, a citizen of the United States, residing at Chicago, in the county of Cook and State of Illinois, and OSWALD JESSL, a citizen of the Republic of Germany, residing at Chicago, in the county of Cook and State of Illinois, U. S. A., have invented a new, original, and ornamental Design for Combination Toothbrush, Paste, and Glass Holders, of which the following is a specification, reference being had

to the accompanying drawing, forming part thereof.

The figure is a perspective view of a combination toothbrush, paste and glass-holder, showing our new design.

We claim:

The ornamental design for a combination toothbrush, paste, and glass holder as shown.

KARL FROST,
OSWALD JESSL.
